UNITED STATES PATENT OFFICE.

WALTER RIEFSCHNIDER AND HENRY RIEFSCHNIDER, OF SEATTLE, WASHINGTON.

SAFETY RAIL JOINT.

Application filed February 19, 1923. Serial No. 619,870.

To all whom it may concern:

Be it known that we, WALTER RIEFSCHNIDER and HENRY RIEFSCHNIDER, citizens of the United States, residing at Seattle, county of King, and State of Washington, have invented new and useful Improvements in Safety Rail Joints; and we do hereby declare that the following is a full, clear, and exact specification, such as will enable others skilled in the art to which it appertains to make and use the same.

The invention is a means for connecting rails that will make it impossible for them to become disconnected or to bend at the connection.

The invention is an improvement over the joint shown and described in our Patent No. 1,439,191 issued December 19, 1922.

The object of the invention is to provide rails with ends which will dovetail together so that it will be impossible for them to spread without tearing up the entire track.

With these ends in view the invention embodies a rail with the top of the rail omitted a short distance from the end, its web thickened with the sides tapering; and another rail with angle plates extending beyond the end of the rail and integral therewith; and a slot with tapering sides between the angle plates. The invention also embodies a clamp for holding the ends of the rails up into the slots of the other rails.

Other features and advantages of the invention will appear from the following description taken in connection with the drawings, wherein:

Figure 1 is a side elevation with parts broken away.

Figure 2 is a cross section through the joint.

Figure 3 is a view showing an alternate design of the clamp at the bottom of the joint.

Figure 4 is a similar view showing another alternate design of the clamp.

Figure 5 is a bottom view of the female member.

Figure 6 is a perspective view of the male member.

In the drawings we have shown our joint as it would appear in use in Figure 1 wherein numeral 1 indicates one rail on which is the female joint and numeral 2 indicates another rail the end of which constitutes the male member. The web of the rail 2 is thickened from the point 3 shown in Figure

1 and tapers from its upper edge 4 to its lower edge 5 where it is curved. This web fits into a slot 6 in the center of the rail 1 and extends to the point 7 shown in Figure 60 1. On the sides of the rail 1 are plates 8 and 9 which extend beyond the end of the rail and to the point 10 so that at least two bolts as indicated by the numeral 11 may be placed through the joint on each side of the point 3. 65

The construction of the rail 1 may be more clearly understood from the bottom view shown in Figure 5 which shows the top of the rail stopped or cut away at the line 3, the bottom flange of the rail stopped 70 or cut away at the line 12, the slot 6 which extends from the line 12 to the point 3 in the center of the rail, and the side plates 8 and 9 which extend from the line 12 to the point 13. The lower edges of the side plates 75 8 and 9 extend outward to form flanges 14 and 15 which rest upon the bottom flange of the end of the rail 2.

The construction of the end of the rail 2 as shown in Figure 6 shows the top of the 80 rail stopped or cut away at the point 3, the web thickened and tapering from the point 4 to the point 5, and a portion of the web beyond the point 3 thickened so that it will be flush with the sides of the top of the rail 85 as indicated by the numeral 16. Suitable holes 17 may be placed through the web to correspond with similar holes through the flanges or side plates of the rail 1 so that bolts may be placed through them to hold 90 the joint together.

At the bottom of the section shown in Figure 2 is a clamp 18 which may be constructed as shown, or in one piece with projections 19 extending upward and bent over 95 as shown at the points 20, and projections 21 extending outward through which the clamp may be spiked to the ties. In the design shown the clamp is shown in two halves 100 so that one half may be slipped on each side of the joint. The halves may then be held in place by spikes passing through the projections 21. Or the clamps may be made in one piece and placed over the ends of the rails before the joint is assembled. An alternate design of the clamp is shown in Figure 3 which has a projection 19 on one side and a lug 22 on the other so that it may be passed under the rail, raised to the position shown, and then held in place by spikes. 110 In the design shown in Figure 4 the clamp has a projection 19 on one side and a lug 23

on the other in which is a dove-tail slot 24. A member 25 with a dove-tail projection 26 on it and whose upper end is bent similar to that of the projection 19 may be placed in the slot 24 after the clamp has been placed under the rail, and may be held by a spike 27 as shown.

It will be understood that changes may be made in the construction without departing from the spirit of the invention. One of which changes may be in the omission of the flanges on the bottom of the plates 8 and 9. Another may be in the number of bolts used in either section of the joint. And still another change may be in the shape of any of the members of the joint, or in the design of the clamps.

The construction will be readily understood from the foregoing description, as all rails may be made with one end similar to that of rail 1 and with the other similar to that of rail 2 so that when a track is being laid one rail will fit into another and the two bolted together. It will be seen that by joining the rails in this manner it will be

absolutely impossible for them to come apart even though the bolts may loosen.

Having thus fully described the invention what we claim as new and desire to secure by Letters Patent, is:—

In a rail joint a rail section having its flange terminated short of its end, the web removed between the end of the flange and the end of the rail and replaced by side plates, which extend from a point a short distance behind the point at which the flange terminates to a point beyond the end of the top of the rail, and which have outwardly extending flanges at their lower edges; a companion rail section provided with an enlarged web section and its top terminated a short distance from its end; the enlarged web section and side plates being provided with bolt holes by which the joint may be bolted together; and base plates with extensions projecting upward that clamp the two sections together, and that may be held to the ties by spikes.

WALTER RIEFSCHNIDER.
HENRY RIEFSCHNIDER.
